UNITED STATES PATENT OFFICE

SALVADOR HERREJÓN LÓPEZ, OF MEXICO CITY, MEXICO

SAFETY APPARATUS

Application filed March 10, 1931, Serial No. 521,615, and in Mexico March 12, 1930.

This invention relates to a safety apparatus designed primarily for use in connection with steam generators or boilers, but it is to be understood that an apparatus in accordance with this invention may be used in any connection for which it may be found applicable, and the invention has for its object to provide, in a manner as hereinafter set forth, a weight operable apparatus for automatically controlling the passage of steam pressure from a generator or boiler when something is abnormal in the working of the latter, such as low water for the purpose of shutting off the supply of fuel to the boiler or generator, to discontinue the operation of the latter, for extinguishing the fire in the firebox or for sounding an alarm to direct attention to the abnormal working.

Further objects of the invention are to provide, in a manner as hereinafter set forth, an apparatus for controlling steam pressure for the purpose referred to and which is simple in its construction and arrangement, strong, durable, compact, thoroughly efficient in its use, readily installed with respect to the water space of the generator or boiler, and comparatively inexpensive to set up.

With the foregoing and other objects in view, the invention consists of the novel construction, combination and arrangement of parts as hereinafter more specifically described, and illustrated in the accompanying drawing, wherein is shown an embodiment of the invention, but it is to be understood that changes, variations and modifications can be resorted to which fall within the scope of the claims hereunto appended.

In the drawing wherein like reference characters denote corresponding parts throughout the several views—

Figure 1 is a fragmentary view of a steam boiler or generator showing the adaptation therewith of a safety apparatus in accordance with this invention and with the apparatus illustrated partly in vertical section, partly in elevation and further broken away.

Figure 2 is a section on line A—A Figure 1.

The apparatus includes a water receiver which is vertically disposed and comprises a

cylindrical body portion 1, an upper head 2 and a lower head 3. The heads 2, 3 are of square contour and formed with rounded corners. The diameter of the body portion 1 is less than the width and breadth of the heads 2, 3. The body portion 1 is disposed concentrically with respect to the heads 2, 3. The heads 2, 3 are grooved on their opposed faces as at 4. The grooves align with each other and have packings 5 seated therein. The ends of body portion 1 extend into the grooves 4 and against the packings 5 whereby a seal tight joint is provided. The heads 2, 3 have extending therethrough tie bars 6 and which carry clamping nuts 7 whereby body portion 1 and heads 2, 3 are clamped together.

The head 2 is formed with openings 8, 9, 10, 11 and 12. The openings are arranged inwardly with respect to the body portion 1. The openings 9 and 11 are of greater diameter than the other of said openings and each has a portion of its wall threaded. The head 3 centrally thereof is formed with an opening 13 having its wall threaded. Threadedly engaging with the wall of the opening 9 is a steam pressure conducting line 14. Threadedly engaging with the wall of the opening 11 is a water supply line 15 opening into the chamber 16 provided by the container. The line 14 is adapted to open or communicate with chamber 16 and is normally closed to the latter.

Extending through the opening 8 is the reduced portion 17 of a hanger 18 depending into chamber 16. A nut 19 is carried on the outer end of the portion 17 for the purpose of clamping hanger 18 to head 2. The lower end of hanger 18 is bifurcated as at 20. Extending through the opening 10 is the reduced portion 21 of a hanger 22 which depends in the chamber 16 and is of materially greater length than hanger 18. A nut 23 is carried on the portion 21 of hanger 22 for the purpose of clamping it to head 2. The lower portion of hanger 22 is bifurcated as at 24. Extending through the opening 12 is the reduced portion 25 of a hanger 26 which depends in chamber 16. A nut 27 is carried by portion 25 of hanger 26 for the purpose of

100

clamping the latter to head 2. The lower end of hanger 26 is bifurcated as at 28. A valve guide and seat forming member 29 is secured by screws 30 against head 2 and which communicates with opening 9. The member 29 is arranged against the lower face of head 2 and is interposed between the hangers 18 and 22. Packing means 31 are carried by the hangers and valve seat forming member and abut against the head 2 to provide a seal tight joint.

Arranged within the chamber 16 and seating on head 2 is a vertically shiftable water receptacle 32 having its bottom 33 spaced above seat 3 and from opening 13. The top of receptacle 32 is provided with water inlets 34 and an enlarged opening 35.

Pivoted as at 36 to the bifurcated end of hanger 18 is a beam 37 having pivotally connected therewith as at 38 a valve 39, arranged in the member 29 for closing the line 14 to the chamber 16. The beam 37 extends through the bifurcated lower end of member 29 and the hanger 22 and has its lowering movement limited by a stop 40 carried by the bifurcated lower end of hanger 22. Pivotally connected as at 41 to the bifurcated lower end of hanger 22 and below stop 40 is a lever arm 42. Arranged within the chamber 16 is a pair of spaced, opposed vertical links 43 connected together by cross pieces 44.

The beam 37 extends between and is pivotally connected to the links 43 as at 45. The arm 42 extends between and is pivotally connected to the links 43 as at 46. Extending through the lower ends of the links 43 is a lever arm 47 which is pivotally connected to the links as at 48. The arm 47 extends into the bifurcated lower end of the hanger 26 and is pivotally connected therewith as at 49.

Extending through the opening 35 and into the water in the receptacle 32 is a balance 50 having its upper end formed with a bifurcated lug 51 to which is pivoted, as at 52 the lever arm 42. The top of the receptacle 32 has a bifurcated lug 53 to which is pivotally connected, as at 54 the lever arm 47.

The steam boiler or generator is indicated at 55 and opening into the water space thereof is a pipe 56 carrying on its outer end a T-coupling 57 having one of its legs connected to and opening into the line 15. Attached to another leg of the coupling 57 is a pipe branch 58 which opens into a four-way coupling 59. Leading from one of the legs of the coupling 59 is a pipe branch 60 which is connected to the wall of and communicates with the opening 13. The pipe branch 58 is connected to another of the legs of the coupling 59 and the remaining legs of the coupling 59 are closed by removable plugs 61.

The line 14 is provided with a normally open closure valve 62.

The weight 50 is always acting downward, trying to close the valve 39. This action of weight 50 is counteracted by the water in the receptacle 32 when this receptacle is free of the displacement of the water in the chamber 16, on account of water having been discharged from it towards the boiler, because the minimum low level of water in the same boiler. The action of the weight 50 again overcomes the weight of the receptacle 32, when this receptacle is displaced by the water in the chamber 16, on account of having been filled with the water, momentarily, this chamber 16, because the rise of the water level in the boiler, in condition to cover the aperture by which the chamber 16 communicates with the boiler.

With the aforesaid it is clearly seen that the weight 50 is constantly exercising an effort to maintain closed the valve 39, and that this effort is effective when the receptacle 32 is displaced; it being counteracted or nullified the same effort when the receptacle 32 is without displacement. When the line 14 is open steam pressure will be supplied to sound the alarm to indicate that the boiler or generator is abnormal as well as for the purpose of shutting off the supply of fuel to the boiler or generator, and for discontinuing the operation of the latter by extinguishing the fire in the firebox.

The water from the boiler is not only supplied into the container through opening 13 but also supplied through the top of the container by line 15. When the water in the boiler becomes low it will also be relieved from the container whereby the beam will function to open the valve.

The connections between the opening 13 and water space of the boiler provides for conducting water from the water space to chamber 16 and from the latter to the water space. The pipe 56 provides for conducting water and steam from the boiler to chamber 16.

The receiver is filled with water from the water space of the boiler when the latter is normal. The balance 50 coacts with the receptacle to maintain the valve closed when the boiler is normal. When the boiler is abnormal, the water receding from chamber 16 will cause the lowering of receptacle 32 and cause the operation of the valve shifting mechanism in a direction to open the valve.

What I claim is:

1. In a safety apparatus for steam boilers, a water receiver having a water intake at its top and a water intake at its bottom, water conducting means leading from the water space of the boiler to said bottom intake for supplying water to the receiver at the bottom of the latter, a water conducting line leading from said means to the top

intake, a valve controlled steam pressure outlet at the top of the receiver, a valve for normally closing said outlet when the boiler is normal, a weight controlled mechanism for shifting said valve to open position when the boiler is abnormal and normally retained in inactive position by the water in the receiver when the boiler is normal, and a vertically movable perforated top water containing receptacle within the receiver and pivotally connected to said mechanism for controlling the operation of the latter.

10 5

2. In a safety apparatus for steam boilers, a water receiver having a water intake at its top and a water intake at its bottom, water conducting means leading from the water space of the boiler to said bottom intake for supplying water to the receiver at the bottom of the latter, a water conducting line leading from said means to the top intake, a valve controlled steam pressure outlet at the top of the receiver, a valve for normally closing said outlet when the boiler is normal, a weight controlled mechanism for shifting said valve to open position when the boiler is abnormal and normally retained in inactive position by the water in the receiver when the boiler is normal, and a vertically movable perforated top water containing receptacle within the receiver and pivotally connected to said mechanism for controlling the operation of the latter, said mechanism including a balance slidably extending into said receptacle and a pivoted beam carrying said valve.

3. In a safety apparatus for steam boilers, a water receiver having a water intake at its top and a water intake at its bottom, water conducting means leading from the water space of the boiler to said bottom intake for supplying water to the receiver at the bottom of the latter, a water conducting line leading from said means to the top intake, a valve controlled steam pressure outlet at the top of the receiver, a valve for normally closing said outlet when the boiler is normal, a weight controlled mechanism for shifting said valve to open position when the boiler is abnormal and normally retained in inactive position by the water in the receiver when the boiler is normal, and a vertically movable perforated top water containing receptacle within the receiver and pivotally connected to said mechanism for controlling the operation of the latter, said mechanism being suspended from the top of the receiver and carrying said valve.

4. In a safety apparatus for steam boilers, a water receiver having a water intake at its top and a water intake at its bottom, water conducting means leading from the water space of the boiler to said bottom intake for supplying water to the receiver at the bottom of the latter, a water conducting line leading from said means to the top intake,

65 70 75 80 85 90 95 100 105 110 115 120 125 130

a valve controlled steam pressure outlet at the top of the receiver, a valve for normally closing said outlet when the boiler is normal, a weight controlled mechanism for shifting said valve to open position when the boiler is abnormal and normally retained in inactive position by the water in the receiver when the boiler is normal, a vertically movable perforated top water containing receptacle within the receiver and pivotally connected to said mechanism for controlling the operation of the latter, said mechanism including a balance slidably extending into said receptacle and a pivoted beam carrying said valve, and said mechanism being suspended from the top of the receiver.

70 75 80 85 90 95 100 105 110 115 120 125 130

5. In a safety apparatus for steam boilers, a water receiver having a water intake at its top and a water intake at its bottom, water conducting means leading from the water space of the boiler to said bottom intake for supplying water to the receiver at the bottom of the latter, a water conducting line leading from said means to the top intake, a valve controlled steam pressure outlet at the top of the receiver, a valve for normally closing said outlet when the boiler is normal, a weight controlled mechanism for shifting said valve to open position when the boiler is abnormal and normally retained in inactive position by the water in the receiver when the boiler is normal, a vertically movable perforated top water containing receptacle within the receiver and pivotally connected to said mechanism for controlling the operation of the latter, and said receptacle capable of seating on the bottom of the receiver and having its bottom arranged over and spaced from said bottom intake.

85 90 95 100 105 110 115 120 125 130

6. In a safety apparatus for steam boilers, a receiver having a steam pressure outlet, a permanently open means for conducting water to said receiver at the bottom of the latter when the boiler is normal and for returning water to the boiler and conducting steam from the latter to the receiver when the boiler is abnormal, a conducting line extending from said means for conducting water from the latter to the top of the receiver when the boiler is normal and for conducting steam to the receiver when the boiler is abnormal, a valve for closing said outlet when the boiler is normal, a vertically movable water containing receptacle having its movement controlled by the rise and fall of the water in the receiver and arranged within and communicating with the latter, a valve shifting mechanism pivotally connected to said receptacle and including a balance slidably extending into the latter, said mechanism acting to close the valve on the upward movement of the receptacle and to open the valve on the lowering of the latter.

105 110 115 120 125 130

7. In a safety apparatus for steam boilers, a receiver having a steam pressure outlet, a

130 135

permanently open means for conducting water to said receiver at the bottom of the latter when the boiler is normal and for returning water to the boiler and conducting steam from the latter to the receiver when the boiler is abnormal, a conducting line extending from said means for conducting water from the latter to the top of the receiver when the boiler is normal and for conducting steam to the receiver when the boiler is abnormal, a valve for closing said outlet when the boiler is normal, a vertically movable water containing receptacle having its movement controlled by the rise and fall of the water in the receiver and arranged within and communicating with the latter, a valve shifting mechanism pivotally connected to said receptacle and including a balance slidably extending into the latter, said mechanism acting to close the valve on the upward movement of the receptacle and to open the valve on the lowering of the latter, and means for suspending said mechanism from the top of the receiver.

In testimony whereof, I affix my signature hereto.

SALVADOR HERREJÓN LÓPEZ.
